J. H. WEDIG

HYPOAMPUL SYRINGE

Filed Feb. 9, 1923

Inventor

John H. Wedig.

By

A. M. Plaisted.

Attorney

UNITED STATES PATENT OFFICE.

JOHN H. WEDIG, OF GRANITE CITY, ILLINOIS.

HYPOAMPUL SYRINGE.

Application filed February 9, 1923. Serial No. 617,994.

To all whom it may concern:

Be it known that I, JOHN H. WEDIG, a citizen of the United States, residing at Granite City, in the county of Madison and 5 State of Illinois, have invented certain new and useful Improvements in Hypoampul Syringes, of which the following is a specification.

This invention relates to certain new and 10 useful improvements in hypo-ampul syringes, the peculiarities of which will be hereinafter fully described and claimed.

The main object of my invention is to provide means for hermetically sealing the 15 operative parts of a hypodermic syringe until ready for use,—such parts including a hollow ampullary plunger hermetically sealed and containing a medicament that is thus doubly sealed, but can be readily 20 opened when said tube is fractured at predetermined points and the syringe prepared for use.

In the accompanying drawing on which like reference numerals indicate corresponding parts, Fig. 1 represents a central longitudinal section of a device exemplifying my 25 invention; Fig. 2 a detached portion of said device; Fig. 3, a similar view of the opposite end; Fig. 4, a detached portion forming the main middle part of the device as it appears 30 when the ends are removed from Fig. 1; Fig. 5, a detached view of the main portion of the tube with the piston and plunger removed and the ampullary end of the plunger fractured to give access to the medicament 35 for pouring it into the main portion of the tube; and Fig. 6 a view of the main portion of the tube forming the syringe barrel with the medicament located therein and the 40 plunger inserted ready for use.

2 designates the walls of a tube having the ends 3 and 4 sealed and adapted for ready opening by means of scratches or cut lines on the circumferential outer surface at the 45 planes 5—5 and 6—6. Near the plane 5—5 is mounted a fixed partition 8 in which is centrally secured a cannula needle 9 that is exposed when the end 3 is removed by fracture at the plane 5—5, but meanwhile is protected in the needle chamber 10. On the opposite side of the partition 8 is slidably 50

mounted in the tube, a piston 11 having a reduced end 12 adapted to fit in the end of a plunger provided with a socket 13 formed by constricting the wall of a smaller tube 55 so that it forms a closure at 14 and then swells out again and the outer end 15 is reduced to a neck-like form and sealed, constituting a closed chamber as well as a plunger. The outer end of the plunger is 60 readily fractured at the plane 7—7 after the outer tube is fractured at the plane 6—6 and exposes the ampullary end of the plunger as in Fig. 4. In this chamber is stored a medicament of any suitable form or state, 65 whether gas, liquid or solid, and since it is sealed therein it is doubly protected by the inner tube and the enclosing outer tube, yet may be readily opened and the liquid, or other medicament contained in this chamber 70 16, may be deposited in the chamber 17 between the fixed wall 8 and the piston 11 when replaced in the main portion of the outer tube,—which main portion thus constitutes the barrel of the syringe. The air 75 in said chamber 17, and one or two drops of the liquid or medicament, are expressed by the piston when the needle is erected preliminary to use as a hypodermic syringe.

I claim:

1. A device of the character described comprising a hermetically sealed tube adapted to be fractured at predetermined points and having a fixed partition adapted to form the butt end of a hypodermic syringe, a cannula needle mounted in said partition, and a piston and plunger slidably mounted in said tube,—said plunger forming an inner sealed chamber for a medicament adapted to be used with said syringe. 80

2. A device of the character described comprising a hermetically sealed tube and contained parts adapted to constitute a hypodermic syringe after fracture at predetermined points,—said parts including a 85 sealed ampul containing a medicament and forming a plunger for the syringe.

3. A device of the character described comprising a hermetically sealed tube adapted for circumferential fracture at predetermined points, and an ampul plunger 95 slidably disposed within said tube and hav- 100

ing a medicament hermetically sealed therein and adapted for fracture at the outer ampullate end, substantially as described.

4. In a device of the character described, an inner tube having a constricted portion near one end constituting an integral partition and forming a socket at said end, and a storage chamber for a medicament on the

other side of the partition,—the end of said inner tube opposite the socket end being ¹⁰ ampullate and hermetically sealed, substantially as described.

In testimony whereof I have affixed my signature.

JOHN H. WEDIG.
